FIG.1.

FIG.2.

FIG.3.

FIG.4.

FIG.5.

FIGURE 1 is a perspective view of a hand tool for perforating showing my new design;

FIGURE 2 is a side elevational view thereof;

FIGURE 3 is a top plan view thereof;

FIGURE 4 is a rear end view thereof; and,

FIGURE 5 is a front end view thereof.

The dotted line portion of FIGURE 1 is included for illustrative purposes only.

The opposite side to that shown in FIGURE 2 is the same in appearance and the bottom plan view is the same in appearance as the top plan view of FIGURE 3.

I claim:

The ornamental design for a hand tool for perforating, substantially as shown and described.
